(72) Inventor: **Tom Weiss**, Ladera Ranch, CA (US)

Primary Examiner — Marianne Pandozzi

(**) Term: **14 Years**

(74) *Attorney, Agent, or Firm* — David G. Duckworth; Russo & Duckworth, LLP

(21) Appl. No.: **29/471,736**

CLAIM

(22) Filed: **Nov. 4, 2013**

The ornamental design for a stackable slider beverage container, as shown and described.

(51) **LOC (10) Cl.** 09-01

DESCRIPTION

(52) **U.S. Cl.**

USPC **D9/743**; D9/566; D9/745; D7/509; D7/515; D7/510

FIG. 1 is a top, right, front perspective view of the stackable slider beverage container of my design;

(58) **Field of Classification Search**

FIG. 2 is a bottom, rear, left perspective view thereof;

USPC ..... D7/509—511, 515; D9/570, 564, 566, D9/573, 743, 745; 220/703, 592.16, 220/592.17; 222/143; D21/500; 446/71

FIG. 3 is a front elevation view thereof;

See application file for complete search history.

FIG. 4 is a rear elevation view thereof;

(56) **References Cited**

FIG. 5 is a left elevation view thereof;

U.S. PATENT DOCUMENTS

FIG. 6 is a right elevation view thereof;
